UNITED STATES PATENT OFFICE

2,306,597

LIGHTING SYSTEM

William G. Darley, Cleveland Heights, Ohio, assignor to General Electric Company, a corporation of New York

Application December 18, 1939, Serial No. 309,714

3 Claims. (Cl. 240—78)

My invention relates to interior lighting and more particularly to a lighting unit for use with tubular light sources and combinations thereof for lighting interiors from within the ceiling.

One object of my invention is to provide satisfactory lighting from overhead for interiors by use of tubular light sources. Elongated light sources, such as tubular incandescent and fluorescent discharge lamps commercially available, provide one distinct advantage over other light sources in that they have a large area of low brightness which tends to provide shadowless and glareless lighting. The fluorescent lamps provide still other advantages in that such lamps are available which produce daylight and other colors of light, and are relatively economical to operate.

Another object of my invention is to provide lighting for an interior by incorporating the tubular light sources directly in the ceiling. The lengths of the tubular light sources limits their use to large lighting units which are rather unsightly and costly, but by incorporating said units within the ceiling in accordance with my invention, the unsightliness is eliminated and the cost is greatly reduced.

Still another object of my invention is to provide a lighting unit adaptable for mounting up in the ceiling and preferably of such a size and construction as to fit in properly in commercial block-type ceilings, such as those made of sound-absorbing material. A lighting unit of this type may replace several blocks of the ceiling and thereby effect a considerable saving in labor and in cost of installation.

Still another object of my invention is to provide in a lighting unit using tubular light sources suitable louvers to aid in the distribution of light and prevention of glare.

In the drawing, Fig. 1 is a plan view, as seen from below, of the ceiling of a room in which lighting units are incorporated according to my invention; Fig. 2 is a similar plan view of a section thereof on a larger scale; Fig. 3 is a vertical section through the ceiling along line 3—3 of Fig. 2; Fig. 4 is a vertical section through one of the lighting units on a still larger scale; and Figs. 5 and 6 are vertical sections corresponding to those of Figs. 3 and 4 of a modification thereof.

As shown in Figs. 1 and 2 of the drawing, the light sources are a plurality of tubular lamps 10 which are mounted in separate troughs or reflectors 11 arranged in end to end relation in a plurality of spaced parallel columns. A single continuous trough may be substituted for each column or series of troughs. Where separate

troughs 11 are employed, they conform in length to that of the commercial light sources 10 available and are arranged in multiples as shown according to the size and shape of the area to be illuminated. The amount of light required controls the spacing of the columns of troughs 11, and in some instances may call for spacing between individual troughs in each of the columns as the amount of light emitted by each trough 11 is necessarily controlled somewhat by the light sources available. It is preferred that the troughs 11 and all other parts of the separate lighting unit 12 provided for each light source 10 be mounted up in the ceiling 13 with the open mouth of said trough in line with, or flush with, the lower surface of said ceiling. In the particular instance shown in the drawing, the ceiling is made up of square blocks 14 of sound-absorbing material and each of the lighting units 12 has a width corresponding to that of one of said blocks 14 and a length corresponding to that of a number (four) of said blocks so as to reduce the labor and cost of installation.

The trough 11 of each lighting unit is comprised of a single piece of metal which is shaped as desired to give the proper distribution of light from the specular, semi-specular or matt white inner surface thereof and the desired cut-off to the light source 10. In the particular instance shown in Figs. 1-4, the inner surface of the trough is matt white and is shaped so that a band 15 near the edge is not illuminated to the same high degree as the remainder of the trough in order to break the sharp contrast between the lighted trough 11 and the unlighted ceiling, and so that a 45 degree cut-off is provided to the light source 10, as shown.

The light source 10, in this case a fluorescent type lamp, is mounted on sockets 16 which are located at opposite ends of the lighting unit 12 and extend down through the trough 11 from the box 17 mounted thereon which, in turn, contains the wiring and auxiliary equipment for the lamp. The box 17 extends from end to end of the trough 11 and is sealed by the flat end plates 18 of the lighting unit 12 which have "knock-outs" 19 for continuing the wiring and, if desired, making connection to electrical conduit. The end plates 18 are also cut out for the sockets 16 in order that they may be spaced farther apart and a standard length light source 10 used and the length of the lighting unit 12 conform to that of four ceiling blocks 14. Between end-to-end positioned lighting units 12 only one end-plate 18 is used so that the partition formed thereby con-

forms with the louvers 20 located at regular spaced intervals along each unit 12, and the sockets 16 of said units 12 are back to back.

The louvers 20 are held in place by tongues 21 and 22 at opposite sides thereof which enter slots in the trough 11. The said louvers serve to properly distribute the light length-wise of said trough 11 and prevent the light source 10 from being seen when looking along the said trough 11 in the normal angles of vision. Since the louvers 20 must be moved to allow replacement of lamps in the lighting unit, they are arranged so that they may be swung down out of the way. A downwardly projecting lip 21' on the tongue 21 at the left of the louver 20 keeps it in place. A movement of said louver 20 upward and to the right carries the tongue 21 out of the slot in the trough 11 and allows it to swing about the pin 23 in the other tongue 22 which then holds it in place.

The means of supporting each lighting unit 12 consists partly of the structure also used to keep the sound-proof blocks 14 of the ceiling in place in that the transverse stiffening strips or ribs 24 located at opposite sides of the trough 11 at two different points rest directly on the parallel metal cross bars or rails 25 of the ceiling structure. No other holding means is used and the lighting units 12 must be moved up into place before the adjacent blocks 14 of the ceiling are slipped into position. The procedure consists in first pushing the lighting unit 12 up between the cross bars 25 on which it is to rest until the shoulders 26 on the ribs 24 engage said cross bars 25, then shifting said unit 12 to one side (say to the right) to cause the edge of the right hand cross bar 25 to engage a slot or notch 27 in each of the ribs 24 at that side, and then tilting said lighting unit to carry the lower widened ends of the other (left hand) ribs 24 above the corresponding (left hand) cross bar 25. The lower ends of the ribs 24 at the opposite (right hand) side of the unit 12 are then free to be lifted above the corresponding cross bar 25 after said unit 12 has been shifted over toward the opposite (left hand) side, and the lighting unit 12 needs only to be pushed back (to the right) to be set in place. When the unit is properly positioned the cross bars 24 are engaged by notches 28 in the ribs 24 and are thus prevented from shifting sideward and falling down. The adjacent blocks 14 of the ceiling can now be pushed into place whereupon no sideward movement of the light unit 12 is possible and it cannot fall out under any circumstances. It will be noted that it is not necessary to provide notches 27 in the ribs 24 at both sides of the unit.

Each of the blocks 14, as shown, comprises plate 29 supporting sound-absorbing material 30 and having upstanding edges 31 which slide up between two spring flanges 32 on the cross bars 25.

The modification 12' of my invention shown in Figs. 5 and 6 differs from my lighting unit 12 just described only in the shape of the trough 11'

and louvers 20' corresponding to trough 11 and louvers 20. In this instance, the trough 11' is deeper to provide a 60 degree cut-off from the light source 10 and the louvers 20' are proportionately deeper.

It will be noted that the rows of lighting units 12 and ceiling block members 14 are interchangeable, so that it is possible to add additional lighting units by replacing one or more rows of block members.

What I claim as new and desire to secure by Letters Patent of the United States is:

1. Means of providing interior illuminating comprising a trough-shaped reflector located within the ceiling of said interior, means within and at opposite ends of said reflector for supporting and making electrical connections to a tubular light source extending from end to end thereof, and means for supporting said reflector in an inverted position with its open mouth substantially flush with the said ceiling comprising transverse outwardly projecting ribs attached to the sides of the reflector and resting on the ceiling structure.
2. Means of providing interior illuminating comprising a trough-shaped reflector located within the ceiling of said interior, means within and at opposite ends of said reflector for supporting and making electrical connections to a tubular light source extending from end to end thereof, and means for supporting said reflector in an inverted position with its open mouth substantially flush with the said ceiling comprising transverse outwardly projecting ribs attached to the sides of the reflector and resting on the ceiling structure, the ribs on at least one side of said reflector being notched to permit insertion of said reflector in the ceiling opening in the manner described.
3. Means of providing interior illumination comprising a trough-shaped reflector located within the ceiling of said interior, means within and at opposite ends of said reflector for supporting and making electrical connections to a tubular light source extending from end to end thereof, louvers positioned crosswise in said reflector for directing light downward and for shielding the light source, support means for said louvers permitting displacement thereof to provide access to the light source comprising tongues at opposite sides of each of said louvers extending into slots adjacent the edges of said reflector, a lip portion extending downward from the outer end of the tongue at one side of the louver which prevents said tongue from being withdrawn through the cooperating slot except after an upward movement of the louver, and means attached to the end of the opposite tongue for preventing said tongue from being withdrawn through its cooperating slot to maintain the said side of the louver in engagement with the reflector, and means for supporting said reflector in an inverted position with its open mouth substantially flush with the said ceiling.

WILLIAM G. DARLEY.
